METHOD OF APPLYING PATCHES TO
WOVEN-WIRE CLOTHHugh E. Brown, Cleveland Heights, and Stewart
M. Grant, Bay Village, Ohio, assignors to The
W. S. Tyler Company

Application September 25, 1943, Serial No. 503,762

1 Claim. (CL. 219—10)

This invention relates as indicated to a method of applying patches to woven wire cloth, but has reference more particularly to the application of such patches to Fourdrinier wires, cylinder wires and dandy roll covers.

It has heretofore been the practice in applying woven-wire patches to Fourdrinier cloth, for the purpose of covering cracks in the cloth, to sew the patches to the cloth by a rather slow and laborious process, necessitating shut-down of the paper-mill and the combined efforts of at least two workers. Moreover, the wire stitching used to secure the patches to the cloth was subjected to wear by the rolls over which the cloth passed, so that the threads frequently broke, necessitating further shut-down of the paper-making equipment and additional repairs. A further objection to this practice is that the wire used in applying the patches formed bulgy opaque seams and spots, the effect of which became apparent in the paper in the form of undesirable water-marks.

The present invention has as its primary objects the repair of Fourdrinier cloth or other paper making machine wire screen by means of patches which can be easily and quickly applied to the cloth, which when applied become virtually an integral part of the cloth, and which are so shaped and designed as to resist and tendency of the rolls or the bending of the cloth in passing over rolls to pull them away from the cloth.

Another object of the invention is to repair Fourdrinier cloth or other paper making machine wire screen by means of patches, the application of which to the cloth requires a minimum of equipment and labor, and which do not form objectionable water marks or spots in the paper formed on the repaired or patched cloth.

To the accomplishment of the foregoing and related ends, said invention, then, consists of the method hereinafter fully described and particularly pointed out in the claim; the annexed drawings and the following description setting forth in detail certain means and one mode of carrying out the invention, such disclosed means and mode illustrating, however, but one of various ways in which the principle of the invention may be used.

In said annexed drawings:

Fig. 1 is a perspective view illustrating the manner in which a patch is applied to a Fourdrinier wire in accordance with the invention;

Figs. 2 and 3 illustrate steps in the application of the preferred form of patch to the wire;

Fig. 4 is a diagram of the induction welding circuit which is employed for applying such patches to the wire;

Fig. 5 is a side elevation of the transformer which is employed in the circuit of Fig. 4;

Fig. 6 is a front elevation of the transformer;

Fig. 7 is a view illustrating the manner in which the core of the transformer is built up;

Fig. 8 is a top plan view of the hot electrode employed in the circuit of Fig. 4;

Fig. 9 is a view partly in elevation and partly in longitudinal section of the hot electrode;

Fig. 10 is a top plan view of the cold electrode;

Fig. 11 is a side elevation of the cold electrode;

Fig. 12 is a plan view of a Transite board which may be used in connection with the welding operations;

Fig. 13 is a view similar to Fig. 4, but illustrating the application of a patch to one of the edges of a Fourdrinier wire; and

Figs. 14, 15 and 16 illustrate other forms of patches which may be employed.

Referring more particularly to Figs. 1 to 12 inclusive of the drawings, it will be seen that a circuit such as has been especially designed for the application of patches to a Fourdrinier wire, includes a source of alternating current, which may be of 220 or 110 volts, as represented by the lines L¹ and L² (Fig. 4), a transformer, which is generally designated by the reference character T, a cold electrode C and a hot electrode H, a switch S, which is provided on the handle of the electrode H for energizing and deenergizing the transformer, through a relay R.

The transformer T consists of a pair of end plates 1 and 2, between which are secured, as by means of bolts 3 and nuts 4 laminations 5 of transformer iron forming the magnet or core of the transformer. Mounted on the core thus formed is a primary coil 6 and a secondary coil 7, the latter consisting of approximately 11 turns of #4 square wire.

The primary coil 6 is connected to the lines L¹ and L², and is tapped as at 8, 9, 10 and 11, so as to provide a variable voltage for the secondary coil, which, of course, provides the current for the welding operations to be presently described.

The hot electrode H, which is connected to one end of the secondary coil 7 consists of a handle 12 preferably formed of wood, having an axial bore in one end for the reception of the conductor wire 13 from the secondary coil, and having secured within its opposite end a brass or the like stud 14, which is in electrical contact with the wire 13.

The stud 14 has threaded secured thereto an axle holder 15, preferably formed of aluminum, and having secured therein, as by means of a set screw 16, and element 17, formed of brass wire and bent to provide a portion 18 extending substantially at right angles to the axle holder, and serving as an axle, upon which is rotatably mounted a carbon wheel 19. The wheel 19 has a peripheral surface 20, which is about $\frac{1}{8}$ of an inch in width, and the wheel is mounted on the axle 18 between a flange 21 thereof and a brass

washer 22, which is retained against the wheel 19 by means of a nut 23. A check nut 24 is provided for determining the position of the axle holder 15 on the stud 14.

The handle 12 has mounted in the top thereof a push-button switch 25, which, through wires 26 and 27, controls a relay 28, which, in turn, serves to energize or deenergize the transformer T.

The cold electrode C consists of a heavy disk 29 of brass or the like, having a socket 30 for the reception of the terminal 31 of the other conductor wire 13' from the secondary coil, such terminal being secured within the socket by means of a set screw 32.

In applying a patch to a Fourdrinier wire by means of the induction welder which has been described, the patch 33, shown in this instance as of diamond shape, is laid upon the portion of the cloth 34 which has a tear 35 therein (Figs. 1, 2 and 3), a board 36 of "Transite" or other electrically insulative material being employed to support the portion of the cloth 34 which underlies and surrounds the tear 35.

The cold electrode 29 is then laid upon the cloth at a short distance from the patch 33, and the operator then runs the carbon wheel 19 along and over the edges of the patch 33, shown in Fig. 1, thereby welding or fusing the edges of the patch to the cloth 34.

By using a welding voltage of from 6 to 9 volts at the carbon wheel, the line of welding is scarcely visible, and the openings in the wire cloth and patch along such line are left virtually undisturbed, with the result that the patch does not leave or form objectionable water marks or spots in the paper made on the repaired or patched cloth. In other words, if the patch is made of wire-cloth having a mesh which is substantially the same as, or preferably slightly larger or coarser than that of the Fourdrinier wire, and preferably a smaller wire diameter than that of the Fourdrinier wire, the welding of the patch to the wire will not in any way interfere with the drainage characteristics of the Fourdrinier wire. In this connection, expert paper makers have experienced difficulty in locating marks made by patches on Fourdrinier wire which have been applied by the method which has been described, whereas, in wire repaired by sewing a rip in the wire or by sewing a patch to the wire, the paper became seriously marked in by the areas of the wire which were thus repaired.

It will be further noted that the patch is of such shape or contour and is applied to the cloth in such a manner that its edges extend angularly to the warp and shoot wires of the Fourdrinier wire, instead of being parallel to such warp or shoot wires. This avoids lines of weakness which might develop in cases where the edges of the patch are parallel with the warp or shoot wires of the Fourdrinier wire, and which would tend to produce cracks in the Fourdrinier wire at the junction of the patch with the wire as the result of repeated flexing and stressing of the wire and patch in its passage over the rolls over which the Fourdrinier wire passes. In other words, the patch of the present invention is so designed and so applied to the Fourdrinier wire as to resist to as great an extent as possible any tendency of the patch to be pulled or torn from the wire by the stresses and strains to which the patch is subjected and, at the same time, to avoid the formation of lines of weakness along the lines of welding. This same principle is observed in

the application of a patch to the edge of the Fourdrinier wire, as shown in Fig. 13, wherein, it will be seen that the inner edges of the patch extend angularly to the warp and shoot wires of the Fourdrinier wire.

Instead of using diamond-shaped patches, as described, effects similar to those described in the preceding paragraph may be attained through the use of patches having contours such as shown in Figs. 14, 15 and 16, the arrow, in each case, indicating the direction of movement of the Fourdrinier wire.

Another advantage accruing from the use of the present method of welding patches to Fourdrinier wire is that the patch is entirely on the outside of the wire, that is to say, no portion of the patch nor means of securing the patch to the wire, extends through the wire to the inner or under-surface of the wire. Consequently, there is nothing to be abraded by the rolls over which the Fourdrinier wire runs, and therefore nothing to cause the patch to be eventually torn away from the wire. Heretofore, in sewing a patch to the wire or in attaching the patch to the wire by means of pickets which were extended through the wire and bent to hold the patch in place, the stitches or pickets eventually became abraded by the passage thereof over the rolls and suction box covers with the result that the patches came off the wire.

It may also be noted that the relatively wide surface 20 of the carbon wheel 19 serves not only to transmit the welding current in a desired manner, but is effective to hold the patch in position as it is being welded to the wire, permitting the operator, after he has placed the patch in the desired position to weld the patch to the wire by the use of only one hand, the cold electrode remaining in position due to its own weight. In this manner, patches can be quickly and easily applied to the wire, without removing the wire from its position in the paper-making machine, or shutting down the machine for unduly long periods.

Although the invention has been described particularly with reference to the application of patches to Fourdrinier wire, it is to be understood that it may also be applied to the application of patches to the wire cloth facings of cylinders used in paper making. In general, a voltage range of from about 5 to about 20 volts at the carbon wheel will be employed for such applications.

Other modes of applying the principle of our invention may be employed instead of the one explained, change being made as regards the means and the steps herein disclosed provided those stated by the following claim or its equivalent be employed.

We therefore particularly point out and distinctly claim as our invention:

The method of repairing a tear or the like in a paper making machine metallic wire screen which comprises overlying the portion of said screen surrounding the tear with a metallic wire screen patch; pressing said patch to said machine wire screen along lines extending about said tear and angularly relative to the warp and shoot wires of said machine screen and simultaneously passing current through said pressed portions whereby the wires of the screen patch and the machine wire screen are fused without causing appreciable flowing of the metal thereof.

HUGH E. BROWN,
STEWART M. GRANT.
